JOHN ROWLAND BROWN, OF MANSFIELD, OHIO, ASSIGNOR TO THE OHIO BRASS COMPANY, OF MANSFIELD, OHIO, A CORPORATION OF NEW JERSEY.

COMPRESSOR INDICATING AND RECORDING DEVICE.

1,256,655.

Specification of Letters Patent. Patented Feb. 19, 1918.

Application filed March 3, 1916. Serial No. 81,811.

To all whom it may concern:

Be it known that I, JOHN R. BROWN, a citizen of the United States, residing at Mansfield, in the county of Richland and

5 State of Ohio, have invented certain new and useful Improvements in Compressor Indicating and Recording Devices, of which the following is a specification.

This invention relates to a mechanical 10 device which may be attached to any fluid pressure device for indicating that a certain predetermined pressure has been reached, and for recording the number of times that the predetermined pressure has 15 been applied to the device. The invention consists in the novel construction, combination and arrangement of the parts.

In the accompanying drawings, Figure 1 is a view partly in section of a device 20 constructed in accordance with the principles of my invention and applied to a rail bond compressor; Fig. 2 is a view in elevation of an indicating and recording device; Fig. 3 is a sectional view taken on the line 3—3 25 of Fig. 1; Fig. 4 is a view of the perforated strips shown in Fig. 3; Fig. 5 is a view of a rail bond compressor mechanism of which Fig. 1 is a sectional view, and Fig. 6 is a detail of a modified form of a rail bond 30 compressor.

It has been found in the application of pressure by means of manual application of power, that unless there is some suitable indicating and recording means, the pressure 35 applied by the compressor is exceedingly variable and is very likely to be less than that actually required because of the physical effort which the operator must exert. This is especially true, for example, in installing rail bonds where it is necessary to compress the copper terminal of a bond into a hole in a rail, and where the electrical and mechanical efficiency of the attachment of the bond to the rail depends upon sufficient 45 compression being applied to the bond terminal. The present invention relates to a device for perforating or marking a metal ribbon in a certain manner only when a sufficient pressure is applied to the bond and to 50 the device, the predetermined pressure being regulated by the composition and thickness of the metal strip and the size of the depression or apertures made in the metal strip. In order to describe the construction 55 and operation of this device it will be con-

sidered as applied to a rail bonding mechanism, although, of course, it has a more general application.

In the accompanying drawings, the reference numeral 6 designates generally a frame or casting of a rail bonding mechanism which is adapted to fit over a rail 7, as shown in Fig. 5, with a fixed abutment 8 at one side and a movable member 9 at the other side which bear upon the ends of a bond 10 inserted through the rail, the movable member 9 being attached to a fluid-tight piston 11 in a suitable chamber 12. At one side of the piston it is provided with a guide 13 and a spring 14 and at the other side of the piston the chamber 12 has a tubular connection 15 which, as shown in Fig. 1, is connected to a compressor 17 having an operating handle 17' or to some suitable source of pressure supply, a by-pass 16 being provided 75 controlled by a valve 16' for permitting fluid from the chamber 12 to flow back to the pump or compressor 17, but as this relates only to the application of the present invention it will not be described in detail. 80

Attached to the casting 6 by fastening devices 18 is a frame 19 which has a projection 20 adapted to fit in a suitable recess 21 of the casting and by reason of packing 22 to make a fluid-tight connection 85 therewith. Adjacent the projection 20 is a recess 23 connected by means of a hole 24 with an extension 25 of the tubular connection 15 by which the fluid under compression is directed to the rail bonding device, 90 or to any other fluid pressure device of which it is desired to indicate and record the pressure. Disposed in the recess 23 is a plunger 26 having a packing 27 to make a fluid-tight connection in the recess. At 95 the outer end it is provided with a rounded head 28.

Spaced from the plunger 26 is a punch 29 mounted in a punch guide 30 and adapted to coöperate with a punch die 31. Between 100 the guide and the die is a slot 32 extending through the frame 19 in which a strip 33 (see Figs. 3 and 4) is adapted to slide. At one side of the guide 30 is a recess 34 in which a pawl 35 is seated having a spring 36 which tends to press the pawl against the strip 33. Attached to the outer end of the punch 29 is a lever 37 mounted on a pin 38 and having an arm to which a handle 39 is attached for operating the lever manually, 110

when desired. A lever 40 mounted on the pin 41 makes connection between the plunger 26 and the lever 37, one end of the lever 40 being provided with an abutting surface 42 which engages the head 28 of the plunger and the other end of this lever 40 being provided with a portion 43 which engages a corresponding abutment 44 on the lever 37.

With this construction it is obvious that whenever pressure is applied to the rail bonding mechanism, as shown in Fig. 5, the same pressure will be given to the plunger 26 which, acting on the lever 40, will act on the lever 37 producing a pressure on the punch 29. If the strip 33 is inserted in the slot 32 below the punch, the punch will be held in place until sufficient pressure is applied to the plunger 26 to indent the material 33 or to perforate it. The pressure required to perforate the strip 33 may be determined beforehand so that as soon as the strip is perforated by the punch the operator will know that sufficient pressure is applied to the bonding mechanism. This will become evident to the operator because when the punch perforates the strip the handle attached to the punch or that of the compressor, or both handles will make a sudden jump or movement. The operator then releases the pressure by means of the valve 16 and by operating the handle 39 restores both the plunger 26 and the punch 29 to their previous positions whereupon the strip 33 is moved to bring an unperforated portion opposite the punch, as shown in Fig. 3, whereupon the operation just described is repeated. The strip 33 is pressed in the direction of the arrow in Fig. 3 so that as soon as the pawl 35 is caused to ride up out of one of the perforations in the strip it will pass directly into the perforation just made, when the strip is moved. When the opposite edge of this perforation reaches the pawl 35 it is stopped thereby and the strip is in position for the next operation of the punch.

In actual use the operator of this device is provided with sufficient rail bonds for a day's work, for example, and a strip of metal ribbon sufficient to make enough records to cover the day's work. By proper operation the metal strip records the number of bonds actually installed by the operator and the device insures that the proper pressure has been applied to each bond. As a means of identifying the strips, they may be marked in a manner known or unknown to the operator, to prevent him from substituting strips that are not standard and from deceiving the officials as to the impressions or bonds actually installed.

A slightly different application of the invention is shown in Fig. 6 in which the plunger 9, as shown at one side of the rail

in Fig. 5, is employed. On the other side of the rail a bushing 45 is provided in which a plunger 46 is movable. This plunger is provided with a marking tip 47 and opposite the plunger is a die 48. Between the bushing 45 and the die 48 is a space of sufficient width to contain a member 49 of considerable thickness. When pressure is applied to this bonding device the plunger 46 is pressed into the member 49 with the same pressure exerted on the other side of the rail by the fluid under pressure and the marking tip 47 is pressed into or through the material 49. The impression of the marking tip or the hole is made in the strip or slug 49 which must be made very thick in order to withstand the heavy direct pressure of the bonding mechanism. The operator can tell that the requisite pressure has been applied to the rail bond by the degree of impression made by the marking tip in the member 49 or by the marking tip having entirely punched through the member 49.

What I claim is:

1. The combination with variable fluid pressure applying means; of means, including a punch, actuated by the same pressure, and a movable strip of perforable material opposing the pressure and directly engaged by the punch and perforated by it when sufficient pressure is applied by the punch, for recording the applications of sufficient pressure of said pressure applying means.

2. In a device for recording the application of a variable fluid pressure, a punch actuated by the applied pressure, and a movable strip of perforable material which is directly engaged by the punch and perforated by it only when sufficient pressure is applied.

3. In a device for recording a predetermined pressure, the combination of a fluid pressure operated member actuated by variable pressure, a punch, a mechanical pressure reducing connection between said member and the punch, and perforable material opposing the pressure of and directly engaged by the punch and perforated by it when a predetermined pressure is applied.

4. In a device for indicating and recording a predetermined pressure, the combination with a member actuated by fluid under pressure, a punch, a piece of material adapted to be engaged by the punch and opposing pressure applied thereto, and means for transferring the movement of the said member to the punch to perforate the said material when a predetermined fluid pressure is applied to said member.

5. In a pressure indicating and recording device, the combination with a member actuated by fluid pressure, a punch, a strip of material engaged by the punch, a mechanical connection between the said member and the

punch for permitting motion to the perforating strip, and means for engaging the perforations of the strip to hold it in place for the next perforation by the punch.

5 6. The combination with means for applying fluid pressure, of a device for indicating and recording a predetermined pressure thereof comprising a movable member actuated by fluid under pressure, and material 10 directly engaged by and opposing pressure applied to said member and distinctly marked thereby when a predetermined pressure is applied to the said member.

7. In a fluid pressure indicating and recording device, the combination with a member actuated by fluid under pressure, of a punch, a piece of material adapted to be normally engaged by the punch and opposing pressure applied thereto, a lever connected 20 to the punch, and another lever interposed between the first said lever and the member for transmitting motion to the first named lever and adapted to move the punch to distinctly mark the said material when a predetermined pressure is applied to the said member.

8. In a device for indicating and recording a predetermined fluid pressure, the combination with a member actuated by fluid under 30 pressure, a punch, a strip of material engaged by the punch, connecting levers between the member and the punch for transmitting motion thereto whereby a distinguishing mark is made on the strip by the

punch when a predetermined pressure is applied to said member, and a spring-pressed pawl adapted to engage each distinguishing mark in the said strip to hold the strip in place for the next distinguishing mark. 35

9. In a device for indicating and recording a predetermined fluid pressure, the combination with a member actuated by fluid under pressure, a punch, a strip of material engaged by the punch, connecting levers between the said member and the punch for transmitting motion to the punch when a predetermined pressure is applied to said member for distinctively marking the said strip, and a handle in connection with one of the levers for withdrawing the punch and 45 restoring the said member to their initial 50 positions.

10. The combination with fluid pressure applying means, of a pressure actuated punch, and a movable piece of thin material 55 engaged by the punch and perforated by it when a predetermined pressure is applied, the perforations recording the number of applications of such pressure.

In testimony whereof I have signed my name to this specification, in the presence of two subscribing witnesses, on this 28th day of February, A. D. 1916.

JOHN ROWLAND BROWN.
